DISPLAY DEVICE

Louis E. Shaw, East Orange, N. J., assignor to
Ad Art Craft, Inc., a corporation of Delaware

Application November 19, 1934, Serial No. 753,605

20 Claims. (Cl. 40—126)

This invention relates to an advertising or display device of the type in which colored paper, embossed or otherwise fashioned to produce simulation of vendable articles is arranged in a

5 container or otherwise disposed to give the visual appearance of a top layer of the real articles as such articles are usually displayed in their containers.

The primary object of the invention is to provide 10 a simple form of display device of this type which will visually represent an assembly of the different articles which it is intended to represent, and to effect a more natural and real appearance to the assembly than do similar display 15 articles now in general use.

It has been known heretofore to provide a display device representing a plurality of merchandise such as cigars, candies, fruits and other vendable articles, which display device is formed 20 from a single sheet of material such as paper, folded and embossed to simulate a row of articles, such as the top row of cigars in a cigar box. Such known devices have been constructed heretofore entirely by machine operation and necessarily display, more or less, the stilted regularity and uniformity in appearance imposed by the folding machine on the sheet and thus on the several representations of the separate articles formed by the single sheet.

30 The actual articles, however, are assembled, as in the case of the top layer of cigars, by hand operation and thus disclose slight irregularities and distinctiveness in appearance between the several articles. In a box of real cigars, for instance, any cigar is very apt to be shifted, say longitudinally relative to the next adjacent cigar; one cigar is very apt to differ slightly from another in size and conformation and particularly the several joints or cracks between contiguous cigars are very apt to display slight irregularities and discrepancies. While these variations in the individual real article and particularly in their relative arrangement when assembled for display may be slight, still the accumulated effect is noticeable and can not be easily reproduced in a structure where the embossed simulations are formed by machine operation on a single sheet and tied together without possibility of shifting as in known forms of display devices.

Accordingly another object of the invention ancillary to the above general object is to provide a display device of the type above outlined in which the representations of the different articles are formed separately and are thus capable

of being assembled by manual operation or otherwise varied in the act of assembling them as are the real articles which they are intended to represent.

It has also been known to cover such single 5 embossed sheet with its regular simulation of separate articles, such as cigars, with a single sheet of transparent material, creased and tucked in between the parallel simulations in an effort to reproduce the appearance of a layer of 10 individually wrapped cigars. While such display forms make quite an effective showing when seen with a casual view, still the individual representations are, as a matter of fact, not actually wrapped, and a more attentive inspection 15 reveals the artificiality of the showing.

Accordingly another object of the invention and also contributory to the desideratum of the general object is to provide a display device which will more truly represent an assembly of 20 individually wrapped articles than has been known heretofore and specifically to simulate the top row of a box of separately wrapped cigars.

Broadly this aspect of the invention is attained 25 by providing a plurality of separate and distinct units, dummies, or other fabricated shapes, each representing an individual article; individually wrapping each of them in a transparent wrapper; assembling the embossings so pre-wrapped 30 on a support in a row or in some other desired relation; and finally securing them to the support in the position normally occupied by the exposed row or layer of the reproduced article in a box or other container. The assembly so 35 formed is mounted in the box or other container as is conventional in such devices and secured in place.

Various other objects and advantages of the 40 invention will be in part obvious from an inspection of the accompanying drawing and in part will be more fully set forth in the following particular description of one form of mechanism embodying the invention, and the invention also consists in certain new and novel features of 45 construction and combination of parts herein-after set forth and claimed.

In the accompanying drawing:

Figure 1 is a perspective view of a cigar box containing a display device simulating a top row 50 of individually wrapped cigars and illustrating a preferred embodiment of the invention.

Figure 2 is a plan view of one of the cigar-representing, embossed units shown in Figure 1 before the transparent wrapper is applied thereto. 55

Figure 3 is a similar view after the wrapper and band have been applied.

Figure 4 is a vertical sectional view through the showing of Figure 1 taken axially of one of the embossed units.

Figure 5 is a vertical transverse sectional view through the central portion and at the left-hand side of the display device shown in Figure 1 showing three of the units and associated parts; and

10 Figure 6 is a transverse sectional view through a modified form of one of the embossed units.

Referring to the drawing, there is disclosed an ordinary cigar box 1 with hinged cover 2 and within which is located a display device for 15 simulating the top row of cigars in a box.

As shown in Fig. 2, I provide a plurality of separately formed units in the form of embossings 3 formed of suitable paper or other similar material and colored to represent cigars. These 20 embossings are rounded at each end as indicated at 4 to simulate the shape of a cigar and are provided with side flanges 5 to give the appearance of depth. Before arranging the embossings in the box they are wrapped with cellophane or 25 other transparent wrapping material having its end portions bent downwardly and back upon themselves under-lapping the adjacent ends of the embossings as shown at 6 in Fig. 3 of the drawing for use as a display when advertising a brand 30 of cigars which is cellophane-wrapped. While the illustrated disclosure shows each cigar representation or embossed unit separably wrapped to simulate individually cellophane wrapped cigars, it is obviously within the scope of the disclosure 35 to include within a single wrapper 6, more than one of the cigar forms 3, so as to represent those brands of cigars where two or three are enclosed in a single wrapper and sold as a vendable unit. The usual cigar band 7 may also be arranged 40 on each of the embossings or dummies.

As shown, a supporting member 8 is placed in the box and this supporting member is provided with integral depending flanges or legs 9 whereby it may be arranged in a suitable plane to dispose the upper surfaces of the embossings in the plane normally occupied by the tops of the cigars arranged in the box. Each end of the support is provided with a tab 10 adapted to engage the adjacent sides of the end embossings to retain 45 the row of embossings in place. The embossings may further be retained in position on the support by a suitable adhesive arranged along the bottom portion 11 of the cellophane wrapping or the embossings may be secured to the support 50 by stapling or other suitable means.

It will be apparent that the invention provides means for displaying merchandise such as cigars without actually exposing the stock in the windows or on the counters of the cigar store and 60 thus permit deterioration of the stock. By employing the individual embossings and separately wrapping them in cellophane or other transparent wrappings, a closer simulation of the actual product may be obtained.

65 In the modification shown in Fig. 6, I provide an embossed member 13, having tabs or extensions 14 formed on the central portion between the rounded ends and adapted to be secured to each other by a suitable adhesive or fastening 70 means. This provides an embossed member having sufficient rigidity to permit the transparent wrapper to be applied by the machine normally used for applying such wrappers to cigars in those cases where the channel shaped embossings 75 shown in Figure 6 do not provide sufficient rigidity

to permit them to be fed through the wrapping machine.

I claim:

1. A display device comprising an open top box, a plurality of separate, long, narrow embossings each having its upper exposed surface fashioned to represent the similarly exposed upper side of a cigar and said embossings being arranged side-by-side in a row, a plurality of separate wrappers, one for each embossing and 10 each enveloping its associated embossing and held thereby in a distended position, concealed connecting, spacing and supporting means for the embossings, underlying the row of wrapped embossings and fixedly connecting to each other 15 and thus fixedly spacing relative to each other the concealed undersides of all of the wrappers in their arranged relative relation thereby to secure the separate embossings together to form a unit of prearranged wrapped cigar simulations, 20 means for securing the unit to the box in fixed relation to its top to simulate a row of individually wrapped cigars located in the position normally occupied by the top row of cigars in a cigar box.

2. A display device comprising a container, a 25 plurality of separate pre-formed, hollow embossings, each shaped to represent a cigar, a plurality of wrappers, each enveloping at least one of the embossings thereby to form a plurality of separately wrapped cigar-like packages, and means 30 for tying the several packages together in a pre-arranged relative relation and for supporting said enveloped packages in said container in the position normally occupied by a top row of 35 cigars in a cigar box.

3. In a device of the class described, the combination of a display device adapted to fit in a container and fashioned to simulate a top layer of articles commonly displayed in such containers, said device comprising a plurality of separately formed units closely assembled side-by-side to form a layer and connecting means engaging the units solely at their undersides for connecting the undersides of the units in their assembled relation while permitting slight relative movement between the upper exposed sides of the units and means for mounting the layer in the container.

4. In a display device, the combination of means defining two parallel layers, one layer constituting a flat support and the other layer comprising a plurality of separate hollow units assembled on one side of the support and projecting laterally and entirely from said side, the exposed side of said other layer simulating a display of merchandise and means between the support and a plurality of spaced apart points of each hollow unit for securing the hollow units in pre-arranged relative relation to each other on the support and said support in its engagement with the units 60 tending to defeat collapsing of the same.

5. A display device comprising a plurality of separate open-bottom, hollow units disposed in juxtaposition to each other in a single plane, a sheet disposed in off-set relation therefrom in a 65 parallel plane and extending continuously and without break from edge to edge and connecting the open-bottom ends of the units thereby to connect and thus tie together the bottom ends of each of the several units and to connect the units 70 to each other, and said units with the connecting sheet coating to form a single, multi-cellular structure.

6. A multi-cellular display device comprising a plurality of tubular members, each approximately 75

square in cross section adjacent their mid-lengths and arranged in parallel and substantially flat side abutting relation for their entire depth at their midlength; the bottom side of each being integral with the similar side of a next adjacent member whereby the several members are fixedly connected at their bases and otherwise free of each other to permit relative flexing of their upper portions and said units coacting in their abutting relation to mutually resist accidental collapsing of the relatively deep tubular members and the upper side of each member fashioned to display a simulation of an article.

7. In a display device, the combination of a support, a plurality of pre-formed elements each representing an article of commerce, said elements assembled in a row on said support and a pair of tabs, one at each opposite end of the support, each tab engaging the outer side of the adjacent end element and said tabs coacting with the support to retain the row of elements in place.

8. In a device of the class described, the combination of a supporting member provided with means for elevating the same, a plurality of pre-formed paper units, each completely enclosed within a transparent wrapper and located on top of the supporting member, each unit including a top portion and side flanges depending therefrom with the transparent wrapper extending between the side flanges and means for securing the bottom portion of the wrapper to the support, the top portion fashioned to simulate a complete article of commerce.

9. A display device comprising a plurality of separate, long, narrow units disposed in parallel relation, each unit being for the most part channel-shaped in cross section with the channels facing downwardly and the upper sides of the webs thereof each fashioned to simulate a vendable article, a plurality of wrappers, one for each unit, and each completely encircling its associated unit and bridging across the space between the side flanges of each unit and a member engaging the under sides of the wrappers and supporting the several units.

10. A display device comprising means representing a row of articles, the individual representations being slightly spaced from each other and a wrapping sheet of transparent material covering certain of the representations and having its side portions passed down into the space between the said certain representations so covered and the next adjacent representations and underlapping said certain covered representations and having its end portions bent downwardly and back upon themselves underlapping the adjacent ends of the representation.

11. In a display device, the combination of a support, a plurality of units each separately wrapped in an envelope of transparent material and each displaying through the envelope the simulation of a vendable article, said units being opaque and assembled on the support in the prefixed relation in which such vendable articles are usually displayed and means concealed from view by the opaque units for securing the underside of each envelop to the support thereby to fix the wrapped units in their prefixed relation.

12. A display device comprising a supporting member, a plurality of hollow elements carried by said member, the exposed upper face of said elements simulating vendable articles and a plurality of separate wrappers, one for each element and each having a portion thereof located between its associated element and the support and said por-

tions, each secured to the support in spaced apart relation.

13. In a display device, a three-dimensioned plaque comprising separate representations of a plurality of articles disposed adjacent one another, a support therefor and a plurality of separate transparent wrappers, one for each representation, each wrapper covering its associated representation and secured to the support independently of each other.

14. In a display device, a hollow tubular member having its underside open at opposite ends, reducing from its midlength toward one end, having an upper exposed side fashioned to simulate a vendable article and having lapping edge portions defining another side adjacent its midlength to form the member tubular at its midlength.

15. In a display device, a long channel-shaped unit having extensions projecting integrally from each side flange adjacent its center and spaced from opposite ends thus leaving the ends of the unit channel shaped in cross section and of less depth than the depth of the central portion, and forming cantilever extensions from the central portion and the top face of said unit having its opposite ends curving downwardly from its central portion and said extensions lapping and secured to each other to form the central portion of the unit into a tube having sufficient rigidity to permit the feeding of the unit through a wrapping machine.

16. In a display device, a long tubular structure channel shape in cross section for a material portion of its length and comprising a top fashioned to simulate an article of commerce, opposing sides depending from the top and acting to give depth to the device and tabs forming extensions from the sides and mutually over-lapping each other to form a double layer bottom to the device.

17. A hollow unit forming one of a plurality of similar units for use in forming a display device simulating a row of articles, said unit simulating one of said articles and being channel-shaped at its mid-length and reducing in depth therefrom at opposite ends, the flanges of the channel shape disposed parallel to each other and with their lower edges disposed in a single plane and forming supporting feet.

18. A display device comprising an embossing simulating a vendable article, a support therefor having downwardly extending legs and a tubular wrapper of transparent material enveloping said embossing and secured to said support.

19. In a display device, a channel-shaped unit having extensions projecting integrally from each side flange adjacent its center and said unit having its underside open on opposite sides of the extensions, and forming a top portion outlined by a depending flange and said extensions lapping and secured to each other to form the central portion of the unit into a tube having sufficient rigidity to permit the feeding of the unit through a wrapping machine, and a wrapper substantially enclosing said unit underlapping and bridging across the exposed channel underside at opposite ends of the unit.

20. An advertising device comprising an open-top structure visually representing the sides of a cigar box, a display dummy fitted in the structure and coacting therewith to simulate a row of individually wrapped cigars located in the position normally occupied by the top row of cigars in a cigar box, said display device comprising a

- layer of cardboard provided with integral down-turned flanges, a plurality of separate pre-formed units arranged in parallel abutting relation on top of the cardboard layer to form a layer of such units, each unit comprising a pre-formed, hollow sheet paper element embossed and colored to simulate a cigar and a tubular wrapper of
- 5 transparent material enveloping the element to simulate a cellophane wrapped cigar, said wrapper having its ends flattened and the flattened ends each bent down into an out-of-the-way position and means for securing the units in place. 5

LOUIS E. SHAW.
